Application April 30, 1941, Serial No. 391,157

20 Claims. (Cl. 235—61)

My invention relates in general to a mechanism for solving equations which may be solved vectorially and more particularly to a mechanical directional antenna pattern calculator.

While I will describe my invention as being embodied in a mechanical directional antenna pattern calculator, yet it is to be understood that my invention may be embodied in other forms to solve other problems of a similar or varied nature.

The outstanding problem in antenna design is always to control the distribution of the radiated energy in some desired manner. The radiation

In the design of an antenna array, it is electrically possible to mould the radiation pattern in almost any desired manner. As the number of radiators or antennas is increased, a greater degree of control becomes possible. The description will deal with a three-element array, but it is to be understood that my invention may be applied to any number of elements. For a three-element antenna array, the following equation is accepted as a standard for calculating the relative field intensity in any direction, both horizontally and vertically. The relative field intensity, represented by e , is:

$$e = \frac{k}{\sin \theta} \sqrt{\{V_1(\cos l_1 - \cos [l_1 \cos \theta]) + V_2(\cos l_2 - \cos [l_2 \cos \theta]) \cos [S_2 \cos (\phi_2 - \phi) \sin \theta + \psi_2]\}^2 + \{V_3(\cos l_3 - \cos [l_3 \cos \theta]) \cos [S_3 \cos (\phi_3 - \phi) \sin \theta + \psi_3]\}^2 + \{V_2(\cos l_2 - \cos [l_2 \cos \theta]) \sin [S_2 \cos (\phi_2 - \phi) \sin \theta + \psi_2]\}^2 + \{V_3(\cos l_3 - \cos [l_3 \cos \theta]) \sin [S_3 \cos (\phi_3 - \phi) \sin \theta + \psi_3]\}^2} \quad (1)$$

pattern, or space characteristic, is a geometrical description of the manner in which the radiant

When the antenna heights are equal, Equation 1 simplifies to:

$$e = \frac{k [\cos l - \cos (l \cos \theta)]}{\sin \theta} \sqrt{\{V_1 + V_2 \cos [S_2 \cos (\phi_2 - \phi) \sin \theta + \psi_2]\}^2 + \{V_3 \cos [S_3 \cos (\phi_3 - \phi) \sin \theta + \psi_3]\}^2 + \{V_2 \sin [S_2 \cos (\phi_2 - \phi) \sin \theta + \psi_2]\}^2 + \{V_3 \sin [S_3 \cos (\phi_3 - \phi) \sin \theta + \psi_3]\}^2} \quad (2)$$

energy is distributed in space around the radiators or antennas. The horizontal pattern represents the distribution in the ground plane, and the various vertical plane patterns represent conditions in directions at various angles above the horizontal. The patterns are represented in polar graphs and may be drawn in terms of relative or actual field strength or power. The present description will be in terms of relative field intensities.

The field intensity in any direction from one or more antennas which radiate power at the same frequency can be calculated from a standard equation, provided sufficient conditions are known concerning the antennas, their arrangement and the distribution of power to them. The group of antennas used to radiate power is spoken of as the antenna array. The greater the number of antennas in an array, the more time and work is required to calculate the radiation pattern for that array. In order to design an array of antennas to give a definite desired pattern, it is often necessary to determine, by trial, the radiation pattern for several arrays before the correct array is selected. Consequently, a great amount of time and effort is entailed in the design of an antenna array for the purpose of getting a desired field intensity pattern.

The nomenclature used is:

- l₁=height of antenna element No. 1, degrees.
l₂=height of antenna element No. 2, degrees.
l₃=height of antenna element No. 3, degrees.
φ₂=bearing of line drawn from antenna No. 1, which is used as reference point, to antenna No. 2.
φ₃=bearing of line drawn from antenna No. 1 to antenna No. 3.
φ=azimuth angle (zero degrees is considered reference direction).
S₂=spacing, degrees, between antenna No. 1 and antenna No. 2.
S₃=spacing, degrees, between antenna No. 1 and antenna No. 3.
θ=zenith angle (vertical is considered zero degrees).
ψ₂=time phase angle of current flowing in antenna No. 2 with respect to current flowing in antenna No. 1.
ψ₃=time phase angle of current flowing in antenna No. 3 with respect to current flowing in antenna No. 1.
V₁, V₂, V₃=the magnitude of the effective fields radiated by the antenna elements Nos. 1, 2 and 3, respectively, and are proportional to the currents flowing in the respective antenna elements.
k=arbitrary constant.

An object of my invention is the provision of a mechanism adapted to solve equations of the type which may be solved vectorially.

Another object of my invention is the provision of a mechanism adapted to solve equations which may be represented by the general vector equation, $e=k(\vec{V}_1+\vec{V}_2+\dots+\vec{V}_n)$, hereinafter referred to.

Another object of my invention is the provision of a mechanism which will solve for the value of the radical expressed in the Equation 1 and 2 above.

Another object of my invention is the provision of a mechanism for generating a movement corresponding to a cosine function and for transferring the said movement to the rotation of vectors so related to each other and to a fixed vector that the vector sum may be read directly at any position throughout the complete cycle of the generated movement.

Another object of my invention is the provision of a mechanism for generating a movement corresponding to a cosine function and for transferring the said movement to a plurality of conditions which when affected by the generated movement provide for giving a resultant condition at any position throughout the complete cycle of the generated movement.

Another object of my invention is the provision of a mechanism for generating recurrent movement and for transferring the said movement to a plurality of conditions which when affected by the generated movement provide for giving a resultant condition at any position throughout the complete cycle of the generated movement.

Another object of my invention is the provision of varying the generating recurrent motion as to amplitude and phase.

Another object of my invention is the provision of adjusting the magnitude and angle of a vector with respect to a reference position.

Another object of my invention is the provision of a mechanism adapted to facilitate the calculation of the relative field intensity of two or more antenna elements in any direction, both horizontally and vertically.

Other objects and a fuller understanding of my invention may be had by referring to the following description and claims, taken in conjunction with the accompanying drawings, in which:

Figure 1 is a representation in a horizontal plan view of the spacing and the orientation of a three-element antenna array, as set off on my calculating machine for solving for one value of the field in the horizontal pattern, where angle ϕ =zero;

Figure 2 is a representation of the position of the vectors of my calculating machine, as obtainable by the setting in Figure 1 for solving for the said one value of the field in the horizontal pattern;

Figure 3 is a representation similar to Figure 1 for solving for another value of the field in the horizontal pattern with the three-element antenna array rotated through an angle of $\phi=70$ degrees;

Figure 4 is a representation of the position of the vectors of my calculating machine, as obtainable by the setting in Figure 3 for solving for the said another value of the field in the horizontal pattern;

Figure 5 is a polar diagram of a horizontal radiation pattern of the three-element antenna array, as obtainable by my calculating machine,

the resultant relative field for the settings in Figures 1 and 3 being shown at angles of zero and 70 degrees respectively;

Figure 6 is a plan view of the three-element antenna array as actually installed in service;

Figure 7 is a plan view of a calculating machine embodying the features of my invention and is adapted to facilitate the calculation of the relative field intensity in any direction, both horizontally and vertically;

Figure 8 is a representation similar to Figure 3 with the three-element antenna array rotated through an angle of $\phi=20$ degrees, being a representation corresponding to a setting on my machine utilized in determining the setting of my machine to solve for values representing a function of the field in the vertical pattern;

Figure 9 is a representation based upon the setting in Figure 8 and is an elevational view for $\phi=20$ degrees and $\theta=60$ degrees and serves to illustrate how my machine may be set off to solve for values representing a function of the field in the vertical pattern;

Figure 10 is a representation of the position of vectors of my calculating machine, as obtainable for the setting in Figure 9, $\phi=20$ degrees and $\theta=60$ degrees, for solving for a value representing a function of the field in the vertical pattern;

Figure 11 is a vertical pattern at $\phi=20$ degrees, when all antennas are 90 degrees in height;

Figure 12 is a representation similar to Figure 9 and is an elevational view for $\phi=70$ degrees and $\theta=40$ degrees, and illustrates how my machine may be set off to solve for values representing a function of the field in the vertical pattern;

Figure 13 is a representation of the position of the vectors of my calculating machine, as obtainable for the setting in Figure 12, $\phi=70$ degrees and $\theta=40$ degrees, for solving for a value representing a function of the field in the vertical pattern; and

Figure 14 is a vertical pattern at $\phi=70$ degrees when all antennas are 90 degrees in height.

The Equations 1 and 2 above for a three-element array is derived from the vector addition of the three vectors which represent the strength of the signal from each of the three antennas arriving at a common point far removed from the antenna array. Each of the three vectors is dependent only on the radiation from its respective antenna with respect to the reference point or origin. A study of these vectors and their relationship with each other will now be developed, in conjunction with Figure 1 of the drawings, which diagrammatically illustrates a three-element array in horizontal plan view, as set off on my machine in Figure 7.

Antenna No. 1 is chosen as the reference point or origin O, and the angle $\phi=$ zero degrees, establishing a directional reference line for antenna No. 1. Antenna No. 2 is spaced S_2 degrees from antenna No. 1 in a direction ϕ_2 degrees from antenna No. 1 or from the reference line $\phi=0$, drawn through No. 1. Antenna No. 3 is spaced S_3 degrees from antenna No. 1 at an angle of ϕ_3 degrees from the reference line for antenna No. 1. The current in antenna No. 1 is assumed to have a phase of zero degrees, while that of antenna No. 2 is ϕ_2 and that of antenna No. 3 is ϕ_3 degrees with respect to antenna No. 1. The point of observation P may be considered to be anywhere on a circle drawn from the origin O, and it is assumed that the distance from the

point of observation to the array is great enough that lines f_1 , f_2 and f_3 representing the fields respectively for the three antennas, drawn from O to P, No. 2 to P, and No. 3 to P are for all practical purposes parallel. It is further assumed (for simplification) that the observation point P is an integral number of wave-lengths from O, which means that the signal from antenna No. 1 is in time phase with the current in antenna No. 1. Thus, the vector representing the signal from antenna No. 1, being a reference vector, may be drawn at an angle of zero degrees and its length will depend upon the strength of the signal from antenna No. 1. Antenna No. 2 is farther away from P than antenna No. 1 by a magnitude, $S_2 \cos(\phi_2 - \phi)$ degrees. As a result, the signal from antenna No. 2 will arrive at P behind the signal from antenna No. 1 due to the longer path. The delayed arrival of the signal from antenna No. 2 to P due to the longer path is compensated for or overcome by reason of the fact that the signal from antenna No. 2 starts with phase ψ_2 ahead of signal from antenna No. 1. The combination of space and phase results in an equivalent phase of, $S_2 \cos(\phi_2 - \phi) + \psi_2$ degrees by which the signal from antenna No. 2 arrives with reference to the signal from antenna No. 1 at the observation point P. By a similar analysis, the signal from antenna No. 3 arrives with reference to the signal from antenna No. 1 at the observation point P by an equivalent phase of, $S_3 \cos(\phi_3 - \phi) + \psi_3$ degrees.

By letting $S_2 \cos(\phi_2 - \phi) + \psi_2 = \alpha_2$, and $S_3 \cos(\phi_3 - \phi) + \psi_3 = \alpha_3$, then the Equation 2 may be written:

$$e = \frac{k [\cos l - \cos(l \cos \theta)]}{\sin \theta} \sqrt{(V_1 + V_2 \cos \alpha_2 \sin \theta + V_3 \cos \alpha_3 \sin \theta)^2 + (V_2 \sin \alpha_2 \sin \theta + V_3 \sin \alpha_3 \sin \theta)^2} \quad (3)$$

Since $\sin \theta = \sin 90$ degrees = 1, (vertical is considered zero degrees, as θ = zenith angle), the Equation 3 may be expressed as follows:

$$e = K \sqrt{(V_1 + V_2 \cos \alpha_2 + V_3 \cos \alpha_3)^2 + (V_2 \sin \alpha_2 + V_3 \sin \alpha_3)^2} \quad (4)$$

The solving of the radical in Equation 4, being a function of the total field intensity at P due to the radiation from the three-element antennas may be determined as shown in Figure 2 by vector addition, where:

V_1 = The magnitude of the vector representing field due to antenna No. 1 at P.

V_2 = The magnitude of the vector representing field due to antenna No. 2 at P.

V_3 = The magnitude of the vector representing field due to antenna No. 3 at P.

V = The magnitude of the resultant vector representing total field at P.

$\alpha_2 = S_2 \cos(\phi_2 - \phi) + \psi_2$

$\alpha_3 = S_3 \cos(\phi_3 - \phi) + \psi_3$

α = phase of resultant vector V .

By assuming that the value of the radical is the resultant of a sum of group of vectors, then Equation 4 may be written vectorially as:

$$e = K \dot{V} \quad (5)$$

where $\dot{V}$ represents the resultant vector which is equal in magnitude to the radical value.

The vector Equation 5 may be written in its vector component form as follows:

$$e = K(\dot{V}_1 + \dot{V}_2 + \dots + \dot{V}_n) \quad (6)$$

where

$\dot{V}_1$ represents vector No. 1, and includes both magnitude and angle,

$\dot{V}_2$ represents vector No. 2, and includes both magnitude and angle, and

$\dot{V}_n$ represents vector No. n , and includes both magnitude and angle.

For a complete picture of the field pattern for an array, such for example as the pattern shown in Figure 5, the total field must be found for P, a number of times and where P is located at a different angle for the array each time. Usually the field is calculated for P located at intervals of 5 or 10 degrees or any other value throughout the horizontal plane. That is to say, the point P in Figure 1, being a point at which the field intensity is determined, is but one of several points located radially about the origin O for the three antennas Nos. 1, 2 and 3. In the actual field layout, the antennas remain fixed and the observation point is moved in a clockwise direction about the origin of the array.

The embodiment of my invention as shown in Figure 7 is designed to determine the field pattern for a three-element array. It can likewise be used directly for a two-element array. The principle may be also extended to apply to more than three elements. Although the device operates to solve radiation problems, its use is not limited to their solution only. It may be easily adapted to the solution of problems not related to radiation, which involve functions equivalent to those found in the equation for field intensity for antenna arrays or to those which may be solved vectorially. With particular reference to Figure 7, my mechanical di-

rectional antenna pattern calculator comprises generally three main parts; namely, a cosine generator indicated generally by the reference char-

acter 15, a vector system indicated generally by the reference character 16, and motion transmitting means indicated generally by the reference character 17 for transmitting the motions of the cosine generator 15 to the vector system 16. The cosine generator 15 generates a movement corresponding to a cosine function, and the motion transmitting means 17 transmits this motion to the rotation of vectors in my vector system, wherein the vectors are so related to each other and to a fixed vector that the vector sum may be read directly at any position throughout the complete cycle of the generated movement. The cosine generator 15, the vector system 16, and the motion transmitting means 17 are suitably mounted upon a base 24 which may comprise a flat sheet of material of the proper dimensions and thickness.

In the cosine generator arrangement, the reference character A₁ represents antenna No. 1, the reference character A₂ represents antenna No. 2, and the reference character A₃ represents antenna No. 3. The antenna A₁ is located at

the origin, whereas the antenna A₂ is carried by an adjusting arm 20 mounted on top of the plate 24 and the antenna A₃ is carried by an adjusting arm 29 mounted upon the underneath side of the plate 24. The antenna A₂ and the antenna A₃ are arranged to be revolved about

the origin or the antenna A_1 by means of a pointer indicated generally by the reference character I. The pointer I may be rotated throughout a complete circle of 360 degrees which is marked off on the base plate 24 at intervals of 10 degrees. The angle between the pointer I and the horizontal passing through the zero mark represents the angle ϕ and the direction of the pointer I represents the direction toward the observation point P. The adjusting arm 10 which carries the antenna A_2 is arranged to be adjustably mounted upon an elongated block 21 which in turn is carried by a small circular plate 22 arranged to be rotated by the pointer I. The small circular plate 22 is positioned on a large circular plate 23 and the arrangement is such that the small circular plate 22 which carries the adjusting arm 20 may be rotated with reference to the large circular plate 23 by loosening the screws 25 and then turning same to adjustably position the angular location of the antenna A_2 . When the angular position of the antenna A_2 is once located, the screws 25 may again be tightened for anchoring the small circular plate 22 to the large circular plate 23. The pointer I is directly connected to the large circular plate 23 and movements thereof are then transmitted to the small circular plate 22, the elongated block 21 and the adjusting arm 20 to the antenna A_2 . The adjusting arm 20 may be adjusted radially with reference to the origin O or the antenna A_1 by loosening the clamp screw 27 which permits the adjustable arm 20 to be moved longitudinally within the slot of the elongated block 21 which is anchored to the small circular plate 22 by means of the screws 26. When the adjusting arm 20 is properly set, the clamping screw 27 may be tightened for securing the adjusting arm 20 in a fixed position. A graduated scale 28 is provided upon the adjusting arm 20 to indicate the spacing between the antenna A_2 and the antenna A_1 at the origin. The adjusting arm 29 which carries the antenna A_3 and which is mounted upon the underneath side of the plate 24 is arranged to be adjustably positioned in the same manner as that described with reference to the adjusting arm 20 and the antenna A_2 . That is to say, the antenna A_3 may be angularly adjusted with respect to the pointer I and may likewise be radially adjusted with reference to the spacing from the antenna A_1 at the origin. The construction for the mounting of the adjusting arm 29 on the underneath side of the plate 24 is substantially the same as that described with reference to the mounting of the adjusting arm 20 mounted on top of the plate 24. The setting for the antennas A_2 and A_3 is the same as that shown diagrammatically in Figure 1 of the drawings, wherein the angle ϕ_2 for the antenna A_2 is 210 degrees and the angle ϕ_3 for the antenna A_3 is 330 degrees. In my cosine generator 15 shown in Figure 7, the angles ϕ_2 and ϕ_3 are measured in a counter-clockwise direction whereas in Figure 6 which represents the actual field location of the antennas the angles ϕ_2 and ϕ_3 are measured in a clockwise direction. The reason for this is that in the field the observer at the point P is considered as moving bodily in a circle around the origin of the antennas whereas in my machine the observer is considered as remaining stationary and the antennas A_2 and A_3 are rotated bodily about the antenna A_1 at the origin. Thus, in setting off the angular position of the antennas A_2 and A_3 for the angles ϕ_2 and

ϕ_3 , the inner circular scale is used. The outer circular scale is used for the pointer I to indicate the angle ϕ between the pointer I and the horizontal line passing through 0 degrees. The 5 end of the adjusting arm 20 which carries the antenna A_2 is arranged to slide in an elongated slot within a slotted arm 33 having its upper end securely fastened to a traverse member 34 of my motion transmitting means 17. The traverse member 34 is arranged to be longitudinally movable between two spaced fixed rollers 35 on one side and two spaced pivotally mounted rollers 36 upon the other side. The pivotally mounted rollers 36 are carried by a relatively short arm 15 which swings about a pivot point 38 and is adapted to urge the rollers 36 against the side of the traverse member 34 under the tension of a spring 39. The arrangement of the rollers is such that the traverse member 34 may be freely moved 20 longitudinally as the antenna A_2 is revolved by the actuation of the pointer I. In other words, the movements of the traverse member 34 correspond to a cosine function of the angular movements of the pointer I with reference to the horizontal reference line passing through the zero degrees. By a similar construction as that just described, the end of the arm 29 which carries the antenna A_3 upon the underneath side of the plate 24 is arranged to slide within an 25 elongated slot in a slotted arm 40 having its upper end securely connected to a traverse bar 31 mounted upon the underneath side of the plate 24. The traverse member 37 is likewise adapted to move longitudinally between rollers mounted 30 upon the underneath side of the plate 24 in the same fashion as the rollers 35 and 36 are mounted upon the top side of the plate 24. Accordingly, the longitudinal movements of the traverse member 37 correspond to a cosine function of the 35 angle between the pointer I and the horizontal line passing through the zero degree mark. The longitudinal movements of the traverse member 34 and the traverse member 37 are transmitted to my vector system indicated generally by the 40 reference character 16.

In my vector system, the points w , x , y and z represent corners of a vector figure such, for example, as shown in Figure 2 of the drawings. In my machine, the point w is the center of a 45 rotating shaft 42, rotatably mounted in the base plate 24, and carries a pulley 43 positioned upon the underneath side of the plate 24. The pulley 43 is driven or rotated by a flexible member 44 such, for example, as a flexible wire. One end 50 of the wire is anchored to an anchoring block 46 carried upon the right-hand of the traverse member 37 and the other end of the wire is anchored to a spring 47 which is fastened to an intermediate portion of the traverse member 37. The wire upon leaving the anchoring block 46 passes over a pulley 45, upon the left-hand side thereof, then across to the pulley 43 where it is wrapped around one or more times, after which the wire extends across to the right-hand side of the pulley 45 and thence to the spring 47 which 55 is fastened to an intermediate portion of the traverse member 37. The spring 47 maintains the wire under relatively rigid tension so that the longitudinal movements of the traverse member 37 are transmitted to the pulley 43 for rotating the shaft 42. To the upper end of the rotating shaft 42 on the upper side of the plate 24, is mounted a circular graduated scale member 68 and an elongated block 49 in which is 60 adjustably mounted an adjustable vector arm

48. The adjustment of the length of the vector arm 48 may be taken care of by a clamping screw 50. As illustrated, the adjustable vector arm 48 is provided with a graduated scale 52 to facilitate the adjusting of the length of the arm. Mounted upon the end of the adjustable vector arm 48 is a graduated scale member 53 which may be rotated in a plane parallel to the base 24 about a pivot member 54 which connects the graduated scale member 53 to the end of the adjustable vector arm 48. The point z lies in the center of the pivot member 54. The circular scale member 68 and the adjustable vector arm 48 may be adjusted angularly with reference to the rotating shaft 42 by means of a set screw 51 which threadably engages the upper end of the rotating shaft 42.

An adjustable vector arm 59, which takes care of the distance between the points x and y on Figure 2, for example, is pivotally mounted to a swinging arm 57. A circular scale member 69 is likewise adapted to be rotatably connected to the swinging arm 57. The adjustable vector arm 59 and the circular scale member 69 are arranged to rotate about a shaft of which the point x is the center and they both may be adjustably set with reference to the shaft about which they rotate by means of a thumb set clamp 61, which when loose permits the adjustable vector arm 59 and the circular scale member 69 to move relative to the shaft about which they are mounted and which when set or tightened secures the adjustable vector arm 59 and the circular scale member 69 to the shaft about which they revolve. The shaft to which the adjustable vector arm 59 and the circular scale member 69 revolve may be indicated by the reference character 56 and to this shaft is secured a pulley 60 driven by a flexible member such, for example, as a flexible wire indicated by the reference character 62. One end of the wire 62 is anchored to an anchoring member 64 after which it passes over a pulley 63, upon the left-hand side thereof, and then across to the pulley 60 where it is wrapped around one or more times and then back across to the right-hand side of the pulley 63 and then over to a spring 65 anchored intermediate of the traverse member 34. The spring maintains the wire 62 under relatively rigid tension so that longitudinal movements of the traverse member 34 are transmitted to the pulley 60 for rotating the adjustable vector arm 59 and the circular scale member 69 about the point x which is on the center of the shaft 56. As illustrated, the adjustable vector arm 59 is slidably mounted within an elongated block 66 which is adjustably secured to the shaft 56 by the thumb set clamp 61. Upon the end of the adjustable vector arm 59 is pivotally mounted a graduated scale member 70 which may rotate in a plane parallel to the base 24 about a pivot member 55 which connects the scale member 70 to the end of the adjustable vector arm 59. The point y lies in the center of the pivot member 55. The adjustable vector arm 59 is provided with a graduated scale 67 which facilitates the adjusting of the length of the arm between the points x and y. When the adjustable vector arm 59 is once positioned as to its length, it may be set by means of the clamping screw 71.

The swinging arm 57 is arranged to be swung in a plane parallel to the base 24 about a stationary post mounted upon the upper side of the base 24 near the traverse member 34. The

70 swinging arm 57 is secured in a fixed adjustable position by means of a hand set clamp 58 which threadably engages the upper end of the stationary post about which the swinging arm 57 revolves. The adjustable swinging of the swinging arm 57 provides for taking care of the distance between the points w and x such, for example, as shown on Figure 2 of the drawings. The swinging arm 57 is elevated above the plane of the base 24 so that the adjustable vector arm 59 and the graduated scale member 70 may swing in a plane which is above the plane in which the adjustable vector arm 48 and the graduated scale member 53 attached thereto is adapted to rotate. Therefore, the swinging arm 57 may be oscillated in its elevational plane without interfering with the adjustable vector arm 48 and the scale 53 pivotally connected thereto. The distance between the points w and x in Figure 20 7 correspond to the distance between the points w and x, for example, in Figure 2 wherein the two points w and x represent the ends of a vector V₁, which may be designated as a reference vector. In other words, the shafts 42 and 56 represent the ends of a reference vector.

25 The time phase angle ψ_2 of the current flowing in antenna No. 2 with respect to the current flowing in antenna No. 1 is set off on the circular scale member 69, using the line passing through the points w and x as a reference line. The time phase angle ψ_3 of the current flowing in antenna No. 3 with respect to the current flowing in antenna No. 1 is set off on the circular scale member 68, using the line passing through w and x as a reference line. In other words, the zero setting for the scale members 68 and 69 coincide with the reference line passing through the points w and x. As will be observed, the reference line w and x assumes a different position as the swinging arm 57 is moved to vary the distance between the points w and x. In my invention the reference line is scribed off on a separate piece of material or a plate indicated generally by the reference character 45 72. This plate may be made of relatively thin material and is positioned directly upon the base 24 and is arranged to pivot about the shaft 42. The reference line which is marked upon the plate 72 is indicated by the reference character 50 71 and extends from one side of the plate to the other side. The plate is shifted to always keep the reference line 71 in a plane which passes through the points w and x on the shafts 42 and 56. The shifting of the plate 72 about the pivot point of the shaft 42 is arranged to be accomplished by a lever arm 73 having a pin 74 carried thereby which fits within an elongated slot 75. The lever arm 73 has its other end pivotally connected about the stationary post upon which the swinging arm 57 is rotated. The lever arm 73 lies directly on top of the thin plate 72 with the pin 74 engaging the elongated slot 75 and the curvature of the slot 75 is such that for any position of the lever arm 73 the reference line 71 always passes through a plane which contains the points w and x. A scale 78 is positioned adjacent the elongated slot 75 and is calibrated to represent the distance between the points w and x. In other words, the value of the vector V₁ is set off upon the scale 78. The circular scale member 68 is positioned immediately on top of the plate 72 and thus an observer can readily align the marks of the circular scale member 68 with the reference line 71. However, the circular scale member, since

it is mounted upon the swinging arm 57 at an elevation above the plate 72 and the reference line 71, becomes more difficult to align the marks thereon with the reference line 71. To facilitate the alignment of the marks upon the circular scale member 68 with the reference line 71 spaced therebelow by an amount equal to the distance that the circular scale member 69 is positioned above the plane of the base 24, I provide an alignment element 76 which extends radially outwardly from the circular scale member 69. The alignment element 76 may be provided with a sighting line 79 so that the operator may align the sighting line with the reference line 71. The left-hand end of the alignment element 76 is carried by the swinging arm 57 and is arranged to be pivotally connected thereto so that it may be frictionally moved to align the sighting line 79 thereon with the reference line 71 on the plate 72. After the alignment element 76 is positioned so that the sighting line 79 lies in a vertical plane perpendicularly above the reference line 71, then the mark on the circular scale member 69 may be made directly with reference to the sighting line 79 instead of with reference to the line 71 positioned at a spaced distance therebelow. In other words, the alignment element 76 and the sighting line 79 thereon serve as means to facilitate the setting of the circular scale member with reference to the line 71 on the plate 72.

The resultant of the vector is the distance between the points z and y and represents a value which is a function of the relative field intensity in any direction, both horizontally and vertically. The distance between the points z and y may be directly read by the two scales 53 and 70 pivotally connected to the ends of the adjustable vector arms 48 and 59. The scales 53 and 70 both carry marks thereon which when added together give the distance between the points z and y . Inasmuch as the scales 53 and 70 are pivotally connected to the ends of the adjustable vector arms 48 and 59, they may be aligned with each other in any direction to read the distance between the points z and y . In the construction of my device the two scales 53 and 70 revolve in planes slightly separated so that there is no interference between the movement of one scale with respect to the movement of the other scale in their different planes.

In explaining the operation of my device, let it be assumed that the antenna heights are equal and that the value of the relative field intensity, e , is to be calculated for the horizontal pattern under the following prevailing conditions, in which:

$$\begin{array}{lll} V_1=2.5 & S_2=200 & S_3=180 \\ V_2=1.4 & \phi_2=210 & \phi_3=330 \\ V_3=1.3 & \psi_2=220 & \psi_3=140 \end{array}$$

The field V_1 from the antenna No. 1 is set off on the scale 78 so that the pointer of the arm 73 coincides with the mark 2.5. The field V_2 from the antenna No. 2 is set off on the adjustable vector arm 59 so that the graduated scale 67 reads 1.4. The field V_3 from the antenna No. 3 is set off on the graduated scale 52 on the adjustable vector arm 48 at a value of 1.3. The spacing S_2 between antenna No. 1 and antenna No. 2 is set off on the graduated scale 28 of the adjusting arm 20 at a value of 200. The spacing S_3 between the antenna No. 1 and the antenna No. 3 is set off on the graduated scale of the adjusting arm 28 on the underneath side of the base 75

plate 24 at a value of 180. The angle ϕ_2 is set off by angularly positioning the antenna No. 2 at 210 degrees measured upon the inner circular scale for degrees. The angle ϕ_3 is set off by angularly positioning the antenna A₃ on the underneath side of the plate 24 at 330 degrees upon the inner circular scale for degrees. The phase angle ψ_2 is set off on the circular scale member 69 at a value of 220 degrees measured with reference to the reference line 71. The phase angle ψ_3 is set off on the circular scale member 68 at a value of 140 degrees with reference to the reference line 71 or the sighting line 79 on the alignment element 76.

The setting of the cosine generator 15 is shown diagrammatically in Figure 1 and the setting of the vector system 16 is shown diagrammatically in Figure 2. Inasmuch as the magnitude of the effective fields radiated by the antenna elements 20 Nos. 1, 2 and 3 are respectively proportional to the current flowing in the respective antenna elements, I illustrate the magnitude of the vector from w to x as V_1 , the magnitude of the vector from x to y as V_2 , the magnitude of the vector 25 w to z as V_3 , and the magnitude of the resultant vector from z to y as V which represents the value of the radical in Equation No. 4. It is to be observed with reference to Figure 2 that the angle between the vector V_1 and the vector V_3 30 is measured or indicated by α_3 , which in turn equals $S_3 \cos (\phi_3 - \phi) + \psi_3$. Therefore, in setting off the angle on the circular scale member 68 with reference to the reference line 71, the expression $S_3 \cos (\phi_3 - \phi)$ is fixed at zero and this 35 is done by rotating the indicator pointer I until the antenna A₃ is vertical after which the angle of $\psi_3 = 140$ degrees may be directly set off on the circular scale member 68. In a similar manner the antenna A₂ is moved to a vertical position 40 so that the expression $S_2 \cos (\phi_2 - \phi)$ equals zero when setting ψ_2 off on the circular scale member 69 with reference to the reference line 71 or the sighting line 79 of the alignment element 76.

When the machine is once set off, the magnitude of the resultant vector V , being the distance 45 from z to y , is measured directly by counting the sum of the marks on the scales 53 and 70 between the points z and y . In Figure 7 the pointer I is directed to the zero degree reading on the outer circular scale which means that the angle ϕ is zero degrees. The value of the magnitude of the resultant vector V for the setting as shown in Figure 7, is 4.04. The next reading of the resultant magnitude of the vector V is taken 50 when the pointer I is placed upon the 10 degree mark for the outer circular scale of the cosine generator. The readings for the magnitude of the resultant vector V are taken at intervals of 10 degrees for ϕ until the complete cycle of one revolution is finished. For an angle of $\phi = 70$ degrees, the antennas A₂ and A₃ of Figure 7 assume a position as shown diagrammatically in Figure 3 and the system of vectors will assume a position as diagrammatically shown in Figure 4. The individual values of the magnitude of the resultant vector V as determined by the readings on the scales 53 and 70 of my machine in Figure 7 are 55 multiplied by a constant K for obtaining the relative field strength being radiated. The plotting of the values for, e , at 10 degree intervals for the complete cycle of 360 degrees gives the horizontal pattern, such for example as illustrated in Figure 5. The values for, e , at ϕ equals zero degrees and for, e , at θ equals 70 degrees is shown by the polar vector lines in Figure 5.

My invention as illustrated in Figure 7 may also be used to determine the value under the radical in Equation 2 for vertical plane patterns. After the value for the radical is once solved by my machine, the value of the field intensity, e , for any vertical plane pattern may be readily calculated by means of a slide rule which takes care of the factors outside of the radical in Equation 2. The various vertical plane patterns represent conditions in direction at various angles above the horizon, in which the angles may be designated by the angle θ . In solving for a value of the field intensity at P, or a vertical pattern, the location of P is determined by two angles, namely, ϕ and θ . The relative position of the observation point P with reference to the three antennas for the vertical pattern is shown by the combined illustrations in Figures 8 and 9, wherein ϕ equals 20 degrees as shown in Figure 8 and θ equals 60 degrees as shown in Figure 9. The angle θ is measured from the vertical because θ equals the zenith angle where the vertical is considered zero degrees.

In solving for the value of the radical in Equation 2 for obtaining a value of the field intensity for the antenna array at the observation point P shown, for example, in Figures 8 and 9, my indicator I is first moved to 20 degrees on the outer circular scale for degrees. In this position the antennas A_2 and A_3 will assume a position as indicated diagrammatically in Figure 8. This setting takes care of the factor, $\phi=20$ degrees. The next operation in setting up my machine to obtain values for determining the vertical patterns of an antenna array is to lock the traverse members 34 and 37 in a fixed position. As illustrated, this may be accomplished by means of hand operated cams 80 and 81 which when turned engage the sides, respectively, of the traverse members 34 and 37. The cam 80 is mounted above the main base plate 24 and the cam 81 is mounted beneath the base plate 34. When the cams 80 and 81 are clamped respectively against the traverse members 34 and 37 they are constrained in a fixed position as determined by the setting of the pointer I on the 20 degree mark on the outer circular scale for degrees. The next operation for setting up my device to measure values for the vertical pattern is to loosen the adjusting arms 20 and 29 of the cosine generator 16 and position them in horizontal alignment, the antenna A_3 pointing to the mark zero on the outer circular zero scale and the antenna A_2 pointing toward the mark 180 degrees upon the outer circular degree scale. The pointer I is also returned to the zero mark on the outer circular degree scale. The position of the antennas A_1 , A_2 and A_3 and the indicator I for the setting just described is the same as that illustrated diagrammatically in Figure 9. The antennas A_2 and A_3 and the adjusting arms 20 and 29 which carry them respectively are retightened, and the hand operated cams 80 and 81 are operated to free the traverse members 34 and 37. The machine is now set to take readings at intervals of 10 degrees for the pointer I from horizontal to 90 degrees. The vectors in my vector system 16 will be the same as that shown diagrammatically in Figure 10 for an angle θ equals 60 degrees. The values as indicated upon the scales 53 and 70 for the resultant vector V , which represents the value

of the radical in the Equation 2, are then multiplied by the coefficient of the radical to obtain the relative field intensity, e , for values for the vertical pattern. These values may then be plotted as shown in Figure 11 from the horizontal to 90 degrees. The line OP represents the relative field intensity for ϕ equals 20 degrees and θ equals 60 degrees. In plotting Figure 11, the antennas were assumed to be 90 degrees in height. In determining the vertical values with my machine, the pointer I is moved at 10 degree intervals with reference to the outside circular degree scale from the horizontal to 90 degrees, but the value for θ is a measure of the angle between the indicator I and the vertical of 90 degrees. In other words, for example, when the pointer I is set upon the 30 degree mark, the actual value for θ is 60 degrees because θ is the zenith angle where the vertical is considered zero degrees.

The Figure 12, when taken in combination with the Figure 3 is another diagrammatic representation for ϕ equals 70 degrees and θ equals 40 degrees. The Figure 13 is a representation of the position which my vector system 16 will assume for ϕ equals 70 degrees and θ equals 40 degrees. The Figure 14 is a vertical pattern at ϕ equals 70 degrees when all the antennas are 90 degrees in height and for θ taken from the horizontal to 90 degrees. The line OP in Figure 14 represents the relative field intensity at the angle θ equals 40 degrees as illustrated in Figure 12.

It is to be noted that my machine functions to solve for the value of the radical in the Equation 2 for both horizontal and vertical patterns and that the relative field intensity, e , is thence calculated by multiplying the value of the resultant vector by the coefficient of the radical.

My machine is directly applicable to solve values for a two-element antenna array. This may be done by positioning the point z at the end of the adjustable vector arm 48 directly over the point w of the rotating shaft 42, which is referred to in some of the claims as a member having thereon a reference point. This means that the antenna A_3 becomes ineffective regardless of its positional setting in moving the point z , since it is placed directly above the point w . The relationship between the antenna A_1 and A_2 remains operative in my machine to solve for values for the two-element antenna array.

In a broad sense, my mechanism is adapted to solve the equation which may be represented by the general vector equation,

$$e = K(V_1 + V_2 + \dots + V_n)$$

In a broad structural sense, my invention comprises a mechanism for generating a movement corresponding to a cosine function and for transferring the said movement to a plurality of conditions which when affected by the generated movement provides for giving a resultant condition at any position throughout the complete cycle of the generated movement.

I claim as my invention:

1. A machine for solving equations which may be solved vectorially comprising, in combination, a movable element having thereon two spaced points constituting the ends of a movable vector, a member having thereon a reference point, said reference point and one of said spaced points of the movable vector being spaced apart and constituting the ends of a reference vector, the said reference point and the other of said spaced points of the movable vector constituting the ends of a resultant vector representing a func-

tion of the value to be solved, said movable element being rotatable about the said one of said spaced points thereon, means for determining the resultant vector representing a function of the value to be solved, means for generating a recurrent movement, and means for transmitting the generated movement to the movable element to rotate same about the said one of said spaced points thereon for giving the resultant vector at any position throughout the complete cycle of the recurrent movement.

2. A machine for solving equations which may be solved vectorially comprising, in combination, a movable element having thereon two spaced points constituting the ends of a movable vector, a member having thereon a reference point, said reference point and one of said spaced points of the movable vector being spaced apart and constituting the ends of a reference vector, the said reference point and the other of said spaced points of the movable vector constituting the ends of a resultant vector representing a function of the value to be solved, said movable element being rotatable about the said one of said spaced points thereon, means for determining the resultant vector representing a function of the value to be solved, means for generating a recurrent movement, means for transmitting the generated movement to the movable element to rotate same about the said one of said spaced points thereon for giving the resultant vector at any position throughout the complete cycle of the recurrent movement, and manually adjustable means for varying the distance between the two spaced points on the movable element.

3. A machine for solving equations which may be solved vectorially comprising, in combination, a movable element having thereon two spaced points constituting the ends of a movable vector, a member having thereon a reference point, said reference point and one of said spaced points of the movable vector being spaced apart and constituting the ends of a reference vector, the said reference point and the other of said spaced points of the movable vector constituting the ends of a resultant vector representing a function of the value to be solved, said movable element being rotatable about the said one of said spaced points thereon, means for determining the resultant vector representing a function of the value to be solved, means for generating a recurrent movement, and means including translatory means and rotary means for transmitting the generated movement to the movable element to rotate same about the said one of said spaced points thereon for giving the resultant vector at any position throughout the complete cycle of the recurrent movement.

4. A machine for solving equations which may be solved vectorially comprising, in combination, a movable element having thereon two spaced points constituting the ends of a movable vector, a member having thereon a reference point, said reference point and one of said spaced points of the movable vector being spaced apart and constituting the ends of a reference vector, the said reference point and the other of said spaced points of the movable vector constituting the ends of a resultant vector representing a function of the value to be solved, said movable element being rotatable about the said one of said spaced points thereon, means for determining the resultant vector representing a function of the value to be solved, means for generating a recurrent movement, and means for transmit-

ting the generated movement to the movable element to rotate same about the said one of said spaced points thereon for giving the resultant vector at any position throughout the complete cycle of the recurrent movement, manually adjustable means for varying the distance between the two spaced points on the movable element, and manually adjustable means for varying the distance between the reference point on the said member and said one of said spaced points of the movable vector.

5. A machine for solving equations which may be solved vectorially comprising, in combination, a movable element having thereon two spaced points constituting the ends of a movable vector, a member having thereon a reference point, said reference point and one of said spaced points of the movable vector being spaced apart and constituting the ends of a reference vector, the said reference point and the other of said spaced points of the movable vector constituting the ends of a resultant vector representing a function of the value to be solved, said movable element being rotatable about the said one of said spaced points thereon, means for determining the resultant vector representing a function of the value to be solved, means for generating a cosine movement, and means for transmitting the generated movement to the movable element to rotate same about the said one of said spaced points thereon for giving the resultant vector at any position throughout the complete cycle of the cosine movement.

6. A machine for solving equations which may be solved vectorially comprising, in combination, a first movable element having thereon two spaced points constituting the ends of a first movable vector, a second movable element having thereon two spaced points constituting the ends of a second movable vector, one of said spaced points on the first movable vector and one of said spaced points on the second movable vector being spaced apart and constituting the ends of a reference vector, the other of said spaced points on the first movable vector and the other of said spaced points on the second movable vector constituting the ends of a resultant vector representing a function of the value to be solved, said first movable element being rotatable about the said one of said spaced points thereon, said second movable element being rotatable about the said one of said spaced points thereon, means for determining the resultant vector representing a function of the value to be solved, means for generating a recurrent movement, and means for transmitting the generated movement to the first and second movable elements to rotate same respectively about the said one of said spaced points thereon for giving the resultant vector at any position throughout the complete cycle of the recurrent movement.

7. A machine for solving equations which may be solved vectorially comprising, in combination, a first movable element having thereon two spaced points constituting the ends of a first movable vector, manually adjustable means for varying the distance between said two spaced points, a second movable element having thereon two spaced points constituting the ends of a second movable vector, manually adjustable means for varying the distance between said two spaced points one of said spaced points on the first movable vector and one of said spaced points on the second movable vector being spaced apart and constituting the ends of a reference vector, the

other of said spaced points on the first movable vector and the other of said spaced points on the second movable vector constituting the ends of a resultant vector representing a function of the value to be solved, said first movable element being rotatable about the said one of said spaced points thereon, said second movable element being rotatable about the said one of said spaced points thereon, means for determining the resultant vector representing a function of the value to be solved, means for generating a recurrent movement, and means for transmitting the generated movement to the first and second movable elements to rotate same respectively about the said one of said spaced points thereon for giving the resultant vector at any position throughout the complete cycle of the recurrent movement.

8. A machine for solving equations which may be solved vectorially comprising, in combination, a first movable element having thereon two spaced points constituting the ends of a first movable vector, a second movable element having thereon two spaced points constituting the ends of a second movable vector, one of said spaced points on the first movable vector and one of said spaced points on the second movable vector being spaced apart and constituting the ends of a reference vector, the other of said spaced points on the first movable vector and the other of said spaced points on the second movable vector constituting the ends of a resultant vector representing a function of the value to be solved, said first movable element being rotatable about the said one of said spaced points thereon, said second movable element being rotatable about the said one of said spaced points thereon, means for determining the resultant vector representing a function of the value to be solved, means for generating a recurrent movement, and means including translatory means and rotary means for transmitting the generated movement to the first and second movable elements to rotate same respectively about the said one of said spaced points thereon for giving the resultant vector at any position throughout the complete cycle of the recurrent movement.

9. A machine for solving equations which may be solved vectorially comprising, in combination, a first movable element having thereon two spaced points constituting the ends of a first movable vector, a second movable element having thereon two spaced points constituting the ends of a second movable vector, one of said spaced points on the first movable vector and one of said spaced points on the second movable vector being spaced apart and constituting the ends of a reference vector, the other of said spaced points on the first movable vector and the other of said spaced points on the second movable vector constituting the ends of a resultant vector representing a function of the value to be solved, said first movable element being rotatable about the said one of said spaced points thereon, said second movable element being rotatable about the said one of said spaced points thereon, means for determining the resultant vector representing a function of the value to be solved, means for generating a recurrent movement, and means for transmitting the generated movement to the first and second movable elements to rotate same respectively about the said one of said spaced points thereon for giving the resultant vector at any position throughout the complete cycle of the recurrent movement, said generating means com-

prising a rotating arm and a translatory member interconnecting the rotating arm and the transmitting means to impart a cosine movement to the transmitting means.

- 5 10. A machine for solving equations which may be solved vectorially comprising, in combination, a first movable element having thereon two spaced points constituting the ends of a first movable vector, a second movable element having thereon two spaced points constituting the ends of a second movable vector, one of said spaced points on the first movable vector and one of said spaced points on the second movable vector being spaced apart and constituting the ends of a reference vector, the other of said spaced points on the first movable vector and the other of said spaced points on the second movable vector constituting the ends of a resultant vector representing a function of the value to be solved, said first movable element being rotatable about the said one of said spaced points thereon, said second movable element being rotatable about the said one of said spaced points thereon, means for determining the resultant vector representing a function of the value to be solved, first cosine means for generating a first movement corresponding to a cosine function, second cosine means for generating a second movement corresponding to a cosine function, means for transmitting the first generated movement to the first movable element to rotate same about the said one of said spaced points thereon and means for transmitting the second generated movement to the second movable element to rotate same about the said one of said spaced points thereon, the rotation of the first and second movable element giving the resultant vector at any position throughout the complete cycle of the recurrent movement.

prising at least a first means establishing a condition representing the value of KV_1 and a second means establishing a condition representing the magnitude of KV_n , means for generating a movement corresponding to a cosine function, means for transmitting the generated movement to the second means to modify the second means for establishing a condition representing the value of KV_n , and means governed by the first and second means for giving the value of e at any position throughout the complete cycle of the generated movement.

13. A machine for solving an equation of the general type, $e=K(\dot{V}_1+\dots\dot{V}_n)$ comprising, in combination, a plurality of means adapted to give a resultant condition representing the value of e , said plurality of means comprising at least a first means establishing a condition representing the value of KV_1 and a second means establishing a condition representing the magnitude of KV_n , said second means including a rotating element, means for generating a movement corresponding to a cosine function, means for transmitting the generated movement to the rotating element to modify the second means for establishing a condition representing the value of KV_n , and means governed by the first and second means for giving the value of e at any position throughout the complete cycle of the generated movement.

14. A machine for solving an equation of the general type, $e=K(\dot{V}_1+\dots\dot{V}_n)$ comprising, in combination, a plurality of means adapted to give a resultant condition representing the value of e , said plurality of means comprising at least a first means establishing a condition representing the value of KV_1 and a second means including a rotating element and vector member for establishing a condition representing the magnitude of KV_n , means for generating a movement corresponding to a cosine function, means for transmitting the generated movement to the second means to modify the second means for establishing a condition representing the value of KV_n , and means governed by the first and second means for giving the value of e at any position throughout the complete cycle of the generated movement.

15. A machine for solving an equation of the general type, $e=K(\dot{V}_1+\dots\dot{V}_n)$ comprising, in combination, a plurality of means adapted to give a resultant condition representing the value of e , said plurality of means comprising at least a first means establishing a condition representing the value of KV_1 and a second means establishing a condition representing the magnitude of KV_n , means for generating a recurrent movement, means for transmitting the generated movement to the second means to modify the second means for establishing a condition representing the value of KV_n , and means governed by the first and second means for giving the value of e at any position throughout the complete cycle of the generated movement.

16. A machine for solving an equation of the general type, $e=K(\dot{V}_1+\dots\dot{V}_n)$ comprising, in combination, a plurality of means adapted to give a resultant condition representing the value of e , said plurality of means comprising at least a first means establishing a condition represent-

ing the value of KV_1 , a second means establishing a condition representing the magnitude of KV_2 , a third means establishing a condition representing the magnitude of KV_n , means for generating a recurrent movement, means for transmitting the generated movement to the second means to modify the second means for establishing a condition representing the value of KV_2 , 10 means for transmitting the generated movement to the third means to modify the third means for establishing a condition representing the value of KV_n , and means governed by the first, second and third means for giving the value of e at any position throughout the complete cycle of the generated movement.

17. A machine for solving an equation of the general type, $e=K(\dot{V}_1+\dot{V}_2+\dots\dot{V}_n)$ comprising, 20 in combination, a plurality of means adapted to give a resultant condition representing the value of e , said plurality of means comprising at least a first means establishing a condition representing the value of KV_1 , a second means establishing a condition representing the magnitude of KV_2 , a third means establishing a condition representing the magnitude of KV_n , first cosine means for generating a first movement corresponding to a cosine function, second cosine means for generating a second movement corresponding to a cosine function, means for transmitting the first generated movement to the second means to modify the second means for establishing a condition representing the value of KV_2 , means for transmitting the second generated movement to the third means to modify the third means for establishing a condition representing the value of KV_n , and means governed by the first, second and third means for giving the value of e at any position throughout the complete cycle of the cosine generated movements.

18. A machine for solving an equation of the general type, $e=K(\dot{V}_1+\dot{V}_2+\dots\dot{V}_n)$ comprising, 45 in combination, a plurality of means adapted to give a resultant condition representing the value of e , said plurality of means comprising at least a first means establishing a condition representing the value of KV_1 , a second means establishing a condition representing the magnitude of KV_2 , a third means establishing a condition representing the magnitude of KV_n , first cosine means for generating a first movement corresponding to a cosine function, second cosine means for generating a second movement corresponding to a cosine function, means for transmitting the first generated movement to the second means to modify the second means for establishing a condition representing the value of KV_2 , means for transmitting the second generated movement to the third means to modify the third means for establishing a condition representing the value of KV_n , and means governed by the first, second and third means for giving the value of e at any position throughout the complete cycle of the cosine generated movements, and means for adjustably shifting one of said cosine generating means relative to the other.

19. A machine for solving an equation of the general type, $e=K(\dot{V}_1+\dots\dot{V}_n)$ comprising, in combination, a plurality of means adapted to give

a resultant condition representing the value of e , said plurality of means comprising at least a first means establishing a condition representing the value of KV_1 and a second means establishing a condition representing the magnitude of KV_n , third means for actuating the second means to modify same for establishing a condition representing the value of KV_n , and means governed by the first and second means for giving the value of e at any actuated position of the third means.

20. A machine for producing a resultant condition from a plurality of individual conditions

comprising, in combination, a plurality of means adapted to give the resultant condition, said plurality of means comprising at least a first means establishing a first individual condition, second means including a rotating element for establishing a second individual condition, means for generating a movement corresponding to a cosine function, means for transmitting the generated cosine movement to the rotating element to modify the condition of the second means, and means governed by the first and second means for giving the said resultant condition.

WILLIAM G. HUTTON.
